US00D513040S

(12) **United States Design Patent** (10) Patent No.: **US D513,040 S**
 Bartholomew et al. (45) Date of Patent: **** Dec. 20, 2005**

(54) **COSMETIC DISPENSER**

(75) Inventors: **Julie R. Bartholomew**, Birmingham, MI (US); **Richard T. Jobe**, Dayton, OH (US); **Thomas C. Bodiker, II**, Englewood, OH (US)

(73) Assignee: **IMX Labs, Inc.**, Birmingham, MI (US)

(**) Term: **14 Years**

(21) Appl. No.: **29/216,713**

(22) Filed: **Nov. 8, 2004**

Related U.S. Application Data

(60) Continuation of application No. 29/192,696, filed on Oct. 28, 2003, now Pat. No. Des. 500,804, which is a division of application No. 29/157,727, filed on Mar. 22, 2002, now Pat. No. Des. 485,310.

Primary Examiner—Robert M. Spear(74) *Attorney, Agent, or Firm*—Dobrusin & Thennisch PC**CLAIM**

The ornamental design for a cosmetic dispenser, as shown and described.

DESCRIPTION

The drawing illustrates a perspective view of a cosmetic dispenser of the present invention. The broken lines in the drawings depict environmental structure, which forms no part of the claimed design.

The broken lines in the drawings represent environmental structure only and form no part of the claimed design.
